MELTING AND DRYING MACHINE

John B. Sweeney, McKeesport, Pa.

Application October 31, 1940, Serial No. 363,760

8 Claims.

This invention relates to a machine for clearing streets, roads, railroad beds or the like of ice and snow, and it is an improvement over the construction disclosed in my co-pending application Serial Number 344,994 filed July 11, 1940.

It is particularly aimed to provide a construction which will first remove excess snow, a construction which has means to break ice before treatment by heat, a construction wherein water is effectively removed on grades as well as at a level, a construction having means effectively coacting with the heating means to collect water and remove the same by suction, a construction having a dryer and a brush in front of the dryer, the latter being adjustable to different angles and novel transmission means for operating the various parts.

The more specific objects will become apparent from a consideration of the description following taken in connection with accompanying drawings illustrating an operative embodiment.

In said drawings:

Figure 1 is a view in plan of the improved apparatus according to the invention;

Figure 2 is a side elevation of the parts of Figure 1;

Figure 3 is a fragmentary plan view showing the brush, its mounting and drive alone;

Figure 4 is a vertical section taken on the plane of line 4-4 of Figure 3;

Figure 5 is a substantially central longitudinal sectional view on an enlarged scale, taken on the plane of line 5-5 of Figure 1;

Figure 6 is an enlarged detail plan view of the reservoir-forming or water collecting blades and associated suction nozzle;

Figure 7 is a detail enlarged cross section showing the parts of Figure 6 from the front, and

Figure 8 is a detail section taken on the line 8-8 of Figure 6.

Referring specifically to the drawings wherein like reference characters designate like or similar parts, a suitable vehicle 10 is employed and by way of example is shown as a truck but it is to be taken as exemplary only since the same function may be performed by other mobile means such as a railroad engine, street car or the like. This vehicle 10 has a body or chassis 11 equipped with rear or propelling wheels 12 and front or steering wheels 13. A cab is provided on the body 11 as at 14. Wheels 13 are steered in a conventional manner and wheels 12 are driven in a conventional manner from an internal combustion engine 15, having a standard or conventional transmission 16 under control 55

of a gear shift lever mechanism 17, such transmission 16 having the usual or conventional drive to the axle means of the propeller wheels 12. Operatively connected to the transmission 16 is 5 an auxiliary transmission mechanism or power take-off means 18, of conventional form.

An extension frame 19 projects forwardly from the frame or chassis 11 and suspended therefrom as by means of cleats or brackets 20 is a heat control box or hood 21, the same being closed at all sides except the bottom, and the latter is spaced an appropriate distance above the roadway or surface being cleared. This heat control box may be interiorly heated in any suitable manner so that ice or snow over which it travels will be subjected to the heat and melted. For instance, burner means 22 may be provided within the hood 21 and receive fuel oil from a tank or reservoir 23 carried by the chassis or body 11, through a valve controlled conduit or the like leading to the burner means 23, such conduit being designated 24.

At the forward end of auxiliary frame 19, a moldboard or plow 25 is suitably supported at 25 any suitable height above the roadway or surface being cleared, it being understood that such moldboard or plow 25 is not intended to remove all snow but only removes it to a certain depth and thus constitutes an excess snow remover. 30 Such excess snow remover 25 is carried by a conventional hydraulic lift mechanism at 26 and the same is adjustable to different positions from the axis of the hydraulic lift 26 and is fastened in any of such adjusted positions by conventional means at 27. A flexible hose 28 leads to the hydraulic lift, passing through guides 29 on the frame 19, and extending into the cab 14 and being operated by conventional hydraulic mechanism disposed therein and under control of the 35 driver, and which mechanism specifically constitutes no part of the invention. Through the operation of the hydraulic lift, the elevation of the excess snow remover 25 with respect to the road bed or surface being cleared may be varied, it being understood that it is held at the different heights by such hydraulic lift.

Between the excess snow remover 25 and the heat control box or hood 21 an ice breaker 30 is located, the same having a shaft or hub 31 which is journaled in brackets 32 extending forwardly from the hood 21. A plurality of breaker tines or teeth 33 project substantially radially from the shaft 31 in order to contact the ice at their free ends and break it, so that when the 55 hood or heat control box 21 passes thereover, its

melting will be facilitated. A sprocket chain 34 is geared to the shaft 31 and is also geared to a loose sprocket wheel 35 carried by a short fixed shaft 36 mounted by auxiliary frame 18. Sprocket wheel 35 is part of a beveled gear wheel 31 enmeshed with a beveled gear wheel 38, carried by a shaft 39 journaled in bearings 40 mounted on the hood or heat control box 21. Such shaft 39 at its other end is suitably connected to and operated from the transmission 16. Shaft 39 includes a clutch or lever operated control mechanism 40, whereby the ice breaker 30 may be placed in or out of operation as preferred. Shaft 39 also is sectional since it includes a universal joint as at 41.

The ice or snow over which the hood 21 passes, is melted by the heat produced and the resulting water is maintained in a pool or restrained to facilitate its removal. It is held in such pool or restrained by angularly disposed bars 42, in effect forming a V, the same being separate and spaced apart as shown or provided in a single piece forming a complete V. Such bars are suspended by links 43, to which they are pivoted as at 44. The links are pivoted at 45 to a crossbar 46, for instance of angular form, riveted as at 47 to the frame 18. The bars 42 may be of angle form as shown and at their inner sides may have squeegee rubber, leather or other flexible strips 48 secured thereto as by rivets or other fastenings 49. The water collected or restrained by the bars 42 is removed by suction through a nozzle 50 which is disposed between the bars 42 adjacent the rear ends thereof. Such nozzle 50 may be connected to the bars 42 and supported thereby. The inlet of the nozzle is an elongated opening 51 at the front and its outlet is in the form of a nipple 52 which is connected to a suction conduit 53 in which a cut-off and regulating valve 54 is interposed. Any suitable means may be provided to cause a suction and eduction through the conduit 53 and for instance a pump as suggested at 55, the discharge from which may be at any desired location.

Auxiliary suction pipes or conduits 56 are provided one on each side of the hood or heat control box 21, being positioned by brackets as at 56'. The forward ends of the auxiliary conduits 56 are open to constitute intakes and they are located adjacent the front end of the hood 21 while the rear ends of the auxiliary conduits 56 are connected to the conduit 53, as well shown in Figure 6, and each has a cut-off and regulating valve 57 therein.

When the vehicle is operating on a level or on upgrades, the suction is effected to remove the water through the nozzle 50 since valve 54 will be open and valves 57 will be closed. However, in travelling downgrade, the water will be removed adjacent the front of the heat control box or hood 21 through the auxiliary conduits 56, since valves 57 will be open and valve 54 closed.

Adjacent the rear of the machine, a suitable rotary brush 58 is provided. Brush 58 is rigid on a shaft or axle 59 journaled in side arms 60, rigidly connected at opposite ends to a transverse rocker shaft 61, having a beveled gear wheel 62 loose thereon and forming part of a sprocket wheel 63 over which a sprocket chain 64 is passed and which is trained over a sprocket wheel 65 rigid on the brush shaft 59. Shaft 61 is journaled in the depending arms 66 of a U-shaped mounting or bracket 67, whose bridge 68 is horizontal and centrally pivoted on a vertical axis at 69 to the frame 11 for movement to position the

brush at different angles, as suggested in Figure 1, to direct swept matter toward a curb or away from the center of the roadway, according to the direction of travel of the vehicle. Said brush 58 is rotated from the auxiliary transmission or power take-off mechanism 18 for instance through the medium of a shaft 70, which is connected by conventional gearing 71 to the beveled gear 62, which accordingly rotates the sprocket wheel 63, chain 64, sprocket wheel 65, shaft 59 and the brush.

The angular position of the brush is varied through operation of a lever mechanism at 72 which is accessible from the driver's seat. Such mechanism has a coacting latch and segment at 73, the latter being mounted on the vehicle, and a link or rod 74 is pivoted to the lever 72 and at its rear end has an eye 75 through which the horizontal member 61 of the wheel bracket passes, and the eye of which eyelet is constructed and arranged as to size and shape to permit such action.

A dryer nozzle 76 is adapted to discharge heated air against the surface or roadway after clearing thereof, and it is located behind the brush 58. This dryer nozzle 76 is open at the bottom and is transversely elongated and of approximately the same width as the vehicle. Such nozzle 76 is suspended from the frame 11 as at 77 and is connected by a pipe or conduit 78 with the rear wall of the heat control box or duct 21, adjacent the top of the latter.

A rotary blower 79, suitably mounted on the frame 11, has a pipe or conduit 80 extending therefrom which opens and discharges into the pipe or conduit 78, being so constructed and arranged that air under pressure from the blower enters the conduit 78 from the conduit 80, in a direction away from the heat control box 21 and toward the nozzle 76. The draft of hot air from said heat control box 21 through the pipe 78 and nozzle 76, in addition to being effected by the action of blower 79, is enhanced by the discharge into the pipe 78 toward the nozzle 76 and relatively close thereto, of exhaust products from the operation of the internal combustion motor 15, through a pipe 81. The muffler in the fuel discharge line from such motor 15 and from which the pipe 81 extends, is shown at 82.

The pump 55 and rotary blower 79, as well as the brush 58, are driven from the auxiliary transmission or power take-off mechanism 18 in any suitable manner, as through flexible shafting and gearing 84 and 85, respectively, leading therefrom.

A conduit 83 communicates with the blower 79 and with the fuel tank 23 so as to place the fuel within the tank 23 under pressure to aid its discharge through the conduit 24 and burner 22 to effectively diffuse the same at the nozzle of the latter.

It will be realized that in operation, excess snow is removed, as the vehicle travels forward, through the action of the remover 25, that ice in the path of travel is broken or crushed by the crusher 30 and that the snow and ice as the hood or heat control box 21 passes thereover is melted and forms a reservoir in front of the bars 42 which is pumped away, on a level or upgrade through the nozzle 50 and conduit 53 while it is pumped away on a downgrade through the nozzles 56 and conduit 53. Thereafter, the surface is engaged by the brush 58, following which it is subjected to the blast of drying air through the nozzle 76.

The excess snow remover 25 insures that the

amount of snow or ice to be removed through the travel of the vehicle is not in excess of the capacity of the vehicle or apparatus.

Various changes may be resorted to provided they fall within the spirit and scope of the invention.

I claim as my invention:

1. A mobile snow removing structure including a mobile body having a forwardly extending frame, means on said frame to heat a roadway, means to remove water produced by the heat, means to remove excess snow from the roadway before subjection to the heat, a crusher for engagement with the roadway located between the excess snow remover and the heating means, power means to propel the mobile body, and a connection on said frame from said power means to the crusher to operate the latter.

2. A mobile snow removing structure including a mobile body, means to heat a roadway, means to remove water produced by the heat, means to remove excess snow from the roadway before subjection to the heat, a crusher for engagement with the roadway located between the excess snow remover and the heating means, power means to propel the mobile body, a connection from said power means to the crusher to operate the latter, including a shaft, a forwardly extending frame on the mobile body from which the heating means is suspended, means journaling said shaft on the heating means, and a drive from said shaft to the crusher.

3. Snow removing means comprising a mobile body, heating means for snow on the roadway over which the vehicle travels, suction means on the body to remove water resulting from the heating means, and nozzle means for the suction means one located adjacent the forward end of the heating means and one adjacent the rear end of the heating means.

4. Snow removing means comprising a mobile body, heating means for snow on the roadway over which the vehicle travels, suction means on the body to remove water resulting from the heating means, nozzle means for the suction means one located adjacent the forward end of the heating means and one adjacent the rear end of the heating means, and valve means to selectively close and open the nozzles.

5. Snow removing means comprising a mobile body, heating means for snow on the roadway over which the vehicle travels, suction means on the body to remove water resulting from the

heating means, nozzle means for the suction means one located adjacent the forward end of the heating means and one adjacent the rear end of the heating means, rearwardly converging bars engaging the roadway in the rear of the heating means to confine water for removal by the adjacent nozzle.

6. Apparatus of the class described comprising a mobile body, a hood carried thereby, means to heat air within the hood so as to melt snow therebeneath, means to remove water resulting from melting of the snow, a nozzle behind the last mentioned means to discharge against the roadway, means establishing communication from said hood to said nozzle, blower means to discharge air into the last mentioned means to facilitate the discharge of heated air through the nozzle.

7. Apparatus of the class described comprising a mobile body, a hood carried thereby, means to heat air within the hood so as to melt snow therebeneath, means to remove water resulting from melting of the snow, a nozzle behind the last mentioned means to discharge against the roadway, means establishing communication from said hood to said nozzle, blower means to discharge air into the last mentioned means to facilitate discharge of heated air through the nozzle, an internal combustion engine to operate the mobile body, said engine having its discharge line connected to the nozzle to facilitate the passage of heated air therethrough.

8. Apparatus of the class described comprising a mobile body, a hood carried thereby, means to heat air within the hood so as to melt snow therebeneath, means to remove water resulting from melting of the snow, a nozzle behind the last mentioned means to discharge against the roadway, means establishing communication from said hood to said nozzle, blower means to discharge air into the last mentioned means to facilitate discharge of heated air through the nozzle, an internal combustion engine to operate the mobile body, said engine having its discharge line connected to the nozzle to facilitate the passage of heated air therethrough, means to contain fuel for supply to the heating means, means to subject said fuel to pressure from said blower, means to remove the water including a pump, and power means operated by the engine to drive the blower, pump and brush.

JOHN B. SWEENEY.
